GRASS CUTTING SHEARS

Edward Albert Rogers, London, England, assignor to
Wilkinson Sword Limited, London, England

Filed Feb. 19, 1971, Ser. No. 117,184

Claims priority, application Great Britain Aug. 29, 1970

Term of patent 14 years

Int. Cl. D8—01

U.S. Cl. D8—5

FIG. 1 is a front perspective view of grass cutting shears showing my new design;

FIG. 2 is a rear elevational view thereof;

FIG. 3 is a side elevation taken from the opposite side to that of FIG. 1; and

FIG. 4 is an underneath plan view showing only the head of the shears and a part of the handles adjacent thereto.

I claim:

The ornamental design for grass cutting shears, as shown.
